DESIGN FOR AN ELECTRIC CIRCULATING FLOOR FAN

Charles E. Jones, Chicago, and Robert H. Crowle,
Berwyn, Ill., assignors to Cory Corporation,
Chicago, Ill., a corporation of Delaware

Application April 2, 1949, Serial No. 1,776

Term of patent 14 years

(Cl. D26—7)

To all whom it may concern:

Be it known that we, Charles E. Jones and Robert H. Crowle, citizens of the United States, residing at Chicago and Berwyn, respectively, in the county of Cook and State of Illinois, have invented a new, original, and ornamental Design for an Electric Circulating Floor Fan, of which the following is a specification, reference being had to the accompanying drawing, forming a part thereof.

In the drawing:

Fig. 1 is a view, in perspective, of an electric circulating floor fan, showing our new design;

Fig. 2 is a side view, in elevation, of the fan; and

Fig. 3 is a top view, in plan, of the fan.

We claim:

The ornamental design for an electric circulating floor fan, substantially as shown.

CHARLES E. JONES.
ROBERT H. CROWLE.
